UNITED STATES PATENT OFFICE.

JOHN L. MORRIS, OF ROXBORO, NORTH CAROLINA.

SIGNALING DEVICE FOR MAIL BOXES.

Application filed October 9, 1923. Serial No. 667,560.

To all whom it may concern:

Be it known that JOHN L. MORRIS, citizen of the United States, residing at Roxboro, in the county of Person and State of North Carolina, has invented certain new and useful Improvements in a Signaling Device for Mail Boxes, of which the following is a specification.

This invention relates to a signaling device for mail boxes and has for its principal object to provide a simple and efficient device which will indicate the presence or absence of mail in the box and is especially adapted for use in boxes used in rural mail delivery.

Another important object of the invention is to provide a signaling device of the above mentioned character wherein means is provided for holding the signaling device in an indicating position when mail is deposited within the box and additional means is provided for returning the signaling element to a non-indicating position when the mail or other contents have been removed from the box.

Another important object of the invention is to provide a signaling device which is so arranged with respect to the mail box as not to interfere with the opening and closing of the same and which may readily be placed in position thereon. The attachment being furthermore supported on the outside of the mail box so as to be accessible at all times.

A further object of the invention is to provide a signaling device of the above mentioned character, which is simple in construction, strong and durable and further well adapted for the purposes for which it is designed.

Other objects and advantages of this invention will become apparent during the course of the following description.

In the drawings forming a part of the specification and in which like numerals designate like parts throughout the same.

Figure 1 is a side elevation of my invention showing the same in an indicating position on a mail box.

Figure 2 is a rear elevation of the same.

Figure 3 is a transverse section taken on line 3—3 of Figure 1.

Figure 4 is a section taken on line 4—4 of Fig. 1.

55 In the drawings wherein for the purpose of illustration is shown the preferred em-

bodiment of my invention, the numeral 1 designates generally the supporting member which is formed of any suitable metallic material and has its longitudinal edges bent inwardly to provide the guide flanges 2 and 3 more clearly shown in Figure 2 of the drawing. For the purpose of securing the supporting member 1 in position on the mail box designated by the letter A, I provide the extensions 4 which extend outwardly from the sides of the supporting member adjacent the forward end thereof, and a similar extension 5 provided in the rear end of the supporting member. These extensions being provided with suitable apertures for receiving fastening means such as bolts, screws or the like for permitting the signaling device to be supported in any suitable manner on a mail box.

These extensions 4 which are formed on the sides of the supporting member adjacent the forward end thereof are formed by transverse parallel incisions in the flanges 2 and 3 so that the portion between the parallel incisions when bent outwardly will form the extensions in the manner shown in the drawings. It is to be furthermore understood that the flange portions 2 and 3 adjacent the forward end of the supporting member extend inwardly for a greater length from the sides as to provide suitable stops 6. The purpose of this arrangement will be hereinafter more fully described.

Adapted for slidable movement on the supporting member 1 and between the longitudinal guide flanges 2 and 3 formed thereon is the signaling element or flag designated by the numeral 7. This flag 7 is adapted to freely slide between the flanges 2 and 3 and is provided at its rear end with the side projections 8, the purpose of which will also be hereinafter more fully described. As further shown in the drawings the supporting member 1 is of a slightly greater length than the signaling element 7 and the latter is so associated with the supporting member as to normally have its forward end extending flush with the forward end of the supporting member. One end of the signaling element or flag 7 is provided with a handle or hook portion designated by the numeral 9 whereby the same may be grasped in order to permit the proper actuation of the flag in the supporting member.

As heretofore described the rear end portion of the signaling element is provided

2
with the outwardly extending projections 8, and it will be seen that upon outward movement of the flag or signaling element 7 the projections 8 are held against the stops 6 5 formed adjacent the forward end of the supporting member 1 and thereby limit the outward movement of the flag when extended in an indicating position. For the purpose of normally holding the flag in an indicating position, I provide a locking device which will be more fully described herebelow. The above mentioned locking device comprises a lever designated by the numeral 10 which tapers smaller from the handle portion 11 to the downwardly extending tongue portion 12. This lever 10 has its intermediate portion provided with downwardly extending ears on its respective sides as shown at 13 in the drawing, and these ears 15 cooperate with the upstanding ears 14 struck up from the supporting member 1 adjacent its forward end. These ears 13 and 14 are provided with registering apertures through which is adapted to extend the supporting 20 pin 15 and whereby the lever 10 may be pivoted on the supporting member 1 in a simple and efficient manner. The tongue portion 12 is provided at the smaller end of the lever 10 and extends through a suitable aperture 25 or slot 16 provided in the supporting member 1 and the axial coil spring 17 which is supported by the pin 15 normally causes the lever 10 to be held in a raised position at its handle portion 11 whereby the tongue 12 30 will normally engage the top face of the sliding flag 7. When the flag 7 has been moved to the outermost extended position, the rear edge portion of the flag will pass the tongue 12 so as to cause the same to extend down against the rear end of the flag 35 and prevent the accidental return of the flag in the supporting member.

Secured at one end to the bottom face of the intermediate portion of the sliding flag 40 45 7 is the coil spring 18. The opposite end of the coil spring 18 is connected in any suitable manner to the rear end portion of the supporting member 1. The purpose of this spring 18 being to normally hold the flag 50 or signaling element 7 in an non-indicating position.

Normally the flag 7 is held within the supporting member 1 by means of the coil spring 18 which indicates that there is no 55 mail within the mail box A upon which my device is mounted. When the mail carrier deposits any mail within the box A, the flag 7 slides by pulling outwardly on the handle 60 9 until the projections 8 come in engagement with the stops 6 and the tongue 12 will then prevent the accidental return of the flag to its normal position within the supporting member thereby indicating to the owner of the mail box that there is mail deposited 65 therein. If desired, the flag 7 may be

colored in any suitable manner as to be visible at a distant point and will thereby save the owner of the mail box the trouble of having to continually walk from his house to the mail box in order to ascertain 70 whether or not there is mail therein for him. The same advantage is had by the mail carrier. It being of course understood that when the person owning the mail box deposits a letter therein for delivery he will 75 actuate the flag to its indicating position in the same manner as the carrier would when depositing letters therein.

After the mail has been removed from the mail box A, the mail carrier or owner of the mail box presses downwardly on the handle portion 11 of the lever 10 so as to cause the tongue to become disengaged from the rear end of the flag and the spring 18 will automatically return the flag to its nonindicating position within the supporting member. 80

In this manner it will be seen that a signal has been provided for use in conjunction with mail boxes principally used in rural mail service which will save considerable time and will also be positive in its action. The simplicity in which my device is operated enables the same to be easily and quickly moved into an indicating or non-indicating position as the case may be and furthermore does not require the alteration or addition of any parts to the mail box in order to provide for the efficient operation thereof. Furthermore by providing a signal of the above mentioned character, the same may be readily removed from a mail box and repaired whenever necessary in a minimum amount of time and the parts are of such a material as to permit the same to be obtained 95 at a minimum cost. 100

From the foregoing description of the construction of my improved apparatus, it will be seen that I have provided a simple, inexpensive and efficient means for carrying out the objects of the invention, and while I have particularly described the elements best adapted to perform the functions set forth, it is obvious that various changes in form, proportion, and in the minor details of construction may be resorted to, without departing from the spirit or sacrificing any of the principles of the invention. 115

Having thus described my invention, what I claim is:

1. In combination with a mail box; of a signal therefor comprising a supporting member, a signaling element slidably mounted thereon, means for limiting the sliding movement of said signaling element, a spring-forced latch pivotally carried on said supporting member and adapted to be automatically engaged with said signaling element and hold the latter in its indicating 125 130 135 position.

position when the same is moved in one direction, and means for automatically returning the signaling element to its non-indicating position upon manually releasing 5 said latch.

2. The combination with a mail box, of a signal therefor comprising a supporting member, a signaling element slidably mounted thereon, a handle carried by said signaling element for moving the same into an indicating position, a lever pivotally supported on said supporting member and adapted for engagement with said signaling element for retaining the same in an indicating position, and resilient means for returning the same to a non-indicating 10 position.

3. The combination with a mail box of a signal therefor comprising a supporting member having its side edges bent inwardly 15 to provide guide flanges, a signaling element slidably supported between said guide

flanges, a handle carried by the forward end of said signaling element for moving the same outwardly into an indicating position, means associated with said flanges adjacent the forward end of said supporting member and the rear end of said signaling element for limiting the outward movement of the latter, a lever pivotally supported on the outer face of said supporting member and having one end thereof extending through a slot in said supporting member and adapted for engagement with the rear end of said signaling element 20 for holding the same in an indicating position, and a coil spring connected with the rear ends of said supporting member and signaling element respectively for returning the latter to a non-indicating position. 25

In testimony whereof I affix my signature.

JOHN L. MORRIS.
